UNITED STATES PATENT OFFICE.

WILLIAM H. BROWNING, OF BAKER CITY, OREGON.

FRUIT-PRESSING APPARATUS.

1,088,123.

Specification of Letters Patent. Patented Feb. 24, 1914.

Application filed May 3, 1913. Serial No. 765,220.

To all whom it may concern:

Be it known that I, WILLIAM H. BROWNING, a citizen of the United States of America, residing at Baker City, in the county of Baker and State of Oregon, have invented 5 certain new and useful Improvements in Fruit-Pressing Apparatus, of which the following is a specification.

This invention relates to certain new and 10 useful improvements in fruit pressing apparatus, and relates more particularly to that type of such devices as are adapted for household use.

The invention has for its main object to 15 provide a device of this character particularly adapted for, though not confined to the crushing or pressing of apples to extract the juice therefrom, and in such a device to provide novel and effective means for effectually crushing and pressing the apple or other 20 fruit so as to most effectually extract the juice.

A further object of my invention is to provide in such a device, a pair of novel 25 crushing-jaws, access to each of which may readily be had for cleansing purposes, as well as to all other parts of the device.

Other objects of my invention are to provide such a device as will be strong and 30 durable, effective for the purpose designed, and comparatively inexpensive to manufacture, and with the above and other objects in view, the invention resides in the novel construction, combination, and arrangement 35 of parts as will be hereinafter more particularly described, and then specifically claimed.

In describing the invention in detail, reference will be had to the accompanying 40 drawings forming a part of this application, and wherein like numerals of reference will be employed for designating like parts throughout the different views of the drawings, in which:

Figure 1 is a view partially in side elevation, and partially in central vertical section, of a fruit press in accordance with my invention. Fig. 2 is an enlarged top plan view of the inner cage and the base or bottom die. Fig. 3 is an enlarged central vertical sectional view of the same, a portion of 50 the cage-wall being broken away. Fig. 4 is a central vertical sectional view of the removable cage, the bottom being broken away. Fig. 5 is a front elevation of the machine

with the press and lever removed. Fig. 6 is a central vertical sectional view of the upper crushing die. Fig. 7 is a view in side elevation of a press with a slightly modified form of container, and, Fig. 8 is an enlarged top plan view of the central supporting post or stud for the inner cage and base or bottom die, the supporting base of the press being broken away.

My invention may assume different embodiments without departing from the spirit involved therein, the embodiment chosen for illustration comprising a base plate 10, which may be made from thin sheet or plate steel or other metal, or cast as desired, and 60 is generally made of a length considerably greater than its width. When made of relatively thin material, it is preferably corrugated to add strength thereto, the corrugations also serving as run-ways for the 65 juice and in any event, said base plate is provided with a main run-way or groove 11 for conducting the juice from the press to a suitable receptacle to catch same. The said plate at its outer end has a downwardly and 70 outwardly projecting lip 12, so that when the plate is securely fastened to a support, as a table, this lip will overhang or project 75 beyond the edge of said table as will be apparent from Fig. 1.

The plate is secured to its support by means of a pair of clamp-arms as 14, the free ends of which extend rearwardly underneath the plate as shown, and have thumbscrews as 15.

Positioned on the plate 10, is a container or receptacle 16, open at its upper and lower ends, and having inwardly extending lugs 17 at its lower end, forming a support for the bottom die, which constitutes the bottom of 80 the inner cage. The wall of the container directly above these lugs is curved as at 17' which tends to guide the inner cage centrally to its seat.

The inner cage is designated as 18, and is 85 received within the container or receptacle 16. Said inner cage is of such diameter, that when fitted within the container 16, a space will be provided entirely around the inner cage as shown, permitting the juice expressed from the fruit to flow readily down onto the base and to the receiver. The said inner cage 18 has its walls perforated as at 18', and these perforations are preferably made oblong, as shown, so as to be less suscep- 90

110

table to filling up with the pumice of crushed apples or like fruit, and also so that the upper die which works within the cage will have a tendency to clean out the perforations as it descends, and carry any pumice sticking in the perforations with the die during such descent.

The bottom die is designated as 19, and this die constitutes the bottom of the inner cage 18. It rests upon and is supported by the lugs 17 of the container 16, and the cage is also supported on the top of the container 16, by an outwardly extending annular flange 20, provided on the upper end of the inner cage. This seals the space between the inner cage and the container at the upper end of the container, and prevents juice from squirting out at the top of the container from such space.

The upper die is designated generally by the numeral 21 and is in the nature of a male die, while the lower or bottom die is in the nature of a female die. Each of these dies have stepped angular faces forming relatively sharp cutting edges when the dies are presented face to face, the bottom die having its horizontally extending faces provided with vertical perforations 21', and its angularly disposed faces provided with horizontally-extending perforations 22. The upper die 21 is similarly provided, in its rim portion 23, with perforations 24, while the core-portion 25 of this upper die may or may not be provided with such perforations. The outer or exposed faces of the dies have an angularity of degree greater than the inner faces, so that all juice thereon will readily drain off.

The base portion 19' of the bottom die 19 is provided with a central enlarged opening 19", which receives a post or stud 26 carried by the plate 10, and forms a support for the bottom die at the center thereof, preventing any crushing down of the die under heavy pressure. The said central opening is made relatively large, so as to permit the insertion of the finger therein to facilitate removal of any pumice that adheres to the die 19. This post is shown in detail in Fig. 8 and has grooved sides so as not to seal the opening 19", and is of a diameter slightly greater than the opening 19", being provided with seats 26' on which the base or bottom die rests.

The upper die 21 is carried on a piston rod or link 27 which extends from said die 21, and at its upper end pivotally connected to a lever 28, the forward end of which is pivotally supported between a pair of forwardly-inclined uprights 29 mounted on the plate 10, near the forward end of the latter. Loosely fitting on the piston rod or link 27 is a lid 30, which when the die 21, which constitutes the piston, descends within the cage 18, rests upon the top of the cage as

shown in Fig. 1, and thus closes the upper end of the cage, and prevents juice squirting out of the cage during the pressing or squeezing of the fruit. All those parts of the device which are subjected to the action of the juices may be suitably coated to prevent rust, or made of material of rust resisting nature, as will be understood.

As heretofore stated, the device is particularly adapted for household use, and is especially adapted for the extraction of the juice from apples for cider, and in such use, the elevating of the lever 28 carries die 21 out of the cage, so that an apple may be placed within the latter in the cup of the bottom die 19. As the lever descends, lid 30 closes the cage at the upper end, and as the apple is crushed by the dies, the expressed juice flows through the perforations of the cage and dies, and to the spout 12. The ready removability of the cage permits the frequent emptying thereof as desired, after each crushing operation, or several crushing operations as wished.

In Fig. 7, a modification of the device is shown, the container designated as 16' being made in two sections suitably hinged, so that one section may be swung aside to permit removal of the cage, the hinged section being suitably fastened when closed in any desired manner. In this construction, I provide the stationary section of the container with an upwardly-extending lip 16" which is slotted to receive the lever 28 for which it acts as a guide, and this lip is concave transversely, so as to also act as a guide for the piston or upper die member when the latter is above the container. The construction of die-members, cage and other parts in this construction are the same as those shown in Fig. 1 and are not illustrated in detail.

While the invention has been described in detail as to the various parts, it will be evident that in the practice of the invention, slight changes and alterations may be made without departing from the general spirit of the invention or the scope thereof as claimed.

Having fully described my invention, what I claim is:

In a fruit press, a supporting base, a post on the base having a grooved periphery and provided at its upper end with seats, an open ended container mounted on the base surrounding the post and having a plurality of inwardly-extending lugs at its lower end, the inner wall of the container above the lugs being curved inwardly, a foraminous cage removably-mounted within the container and of materially less diameter than the container to form a space between the cage and container, a female crushing die constituting the bottom of said cage guided into position by said curved wall of the container and resting on the lugs of the con-

tainer and the seats of said post respectively, an outwardly extending flange at the upper end of said cage overlying the upper end of the container, a male crushing die operative within the cage, a lever pivotally supported from the base, and a rod connecting the male die to said lever.

In testimony whereof I affix my signature in presence of two witnesses.

WILLIAM H. BROWNING.
